Patented Sept. 30, 1975

236,955

COMBINED CLOCK AND CURIO CABINET

Leonard Eisen, 14 Lomas Lane, Montvale, N.J. 07645

Filed Mar. 28, 1974, Ser. No. 455,714

Term of patent 14 years

Int. Cl. D10—01

U.S. Cl. D10—2

FIG. 1.

FIG. 2.

FIG. 1 is a front perspective view of the combined clock and curio cabinet showing my design; and

FIG. 2 is a right side elevational view thereof, the left side being a mirror image thereto.

The rear of the new design is plain and unornamented.

I claim:

The ornamental design for a combined clock and curio cabinet, as shown and described.
